Patented Dec. 16, 1975

238,081

REMOTE STATION FOR DICTATING EQUIPMENT

James C. Sturrock, Atlanta, Ga., assignor to
Robert N. Fink, Decatur, Ga.

Filed Mar. 14, 1974, Ser. No. 451,123

Term of patent 14 years

Int. Cl. D14—01
U.S. Cl. D26—14 B

FIG 1

FIG 2

FIG. 3

FIG. 4

FIG. 5

FIG. 6

FIG. 1 is a perspective view of a remote station for dictating equipment constructed in accordance with our design; the microphone with which the station is operative being shown in broken lines;

FIG. 2 is a top plan view of the remote station for dictating equipment shown in FIG. 1;

FIG. 3 is a left side elevational view of the remote station for dictating equipment shown in FIG. 1;

FIG. 4 is a right side elevational view of the remote station for dictating equipment shown in FIG. 1;

FIG. 5 is a front elevational view of the remote station for dictating equipment in FIG. 1; and

FIG. 6 is a rear elevational view of the station shown in FIG. 1.

The bottom has no design significance.

The broken line representations are shown for illustrative purposes only.

I claim:

The ornamental design for a remote station for dictating equipment, as shown and described.
